Howard C. Thompson
ATTORNEY

UNITED STATES PATENT OFFICE.

JOSEPH SOSS, OF BROOKLYN, NEW YORK.

HINGE.

Application filed March 5, 1927. Serial No. 172,943.

This invention relates to hinges and particularly to devices of this class of the concealed type; and the object of the invention is to provide means whereby the separate butts of the hinge may be secured in position by suitable fastening devices engaging the rear or face portions of the separate butts without the use of attaching devices passed through the front or exposed surfaces as has been the common practice; a further object being to provide a hinge butt which is adapted primarily for use in connection with a stationary support and swinging member composed of sheet metal or partially of sheet metal whereby the screws or other attaching devices may be passed through the sheet metal butts of the stationary support and swinging member and into the respective butts or into engagement therewith for retaining the butts in position, and to accomplish this result without having said screws or attaching devices visible through the front or open ends of the butts, thus producing a neat and finished appearance as well as a rigid mounting for hinges of any kind or class; and with these and other objects in view, the invention consists in a hinge of the class and for the purpose specified, which is simple in construction, efficient in use, and which is constructed as herein-after described and claimed.

The invention is fully disclosed in the following specification, of which the accompanying drawing forms a part, in which the separate parts of my improvement are designated by suitable reference characters in each of the views, and in which:

Fig. 1 is a perspective view indicating the mounting of two hinges in connection with a support or door frame and door.

Fig. 2 is a detail face view of the door frame and door with the door in an open position.

Fig. 3 is a section on the line 3—3 of Fig. 1, but showing the door in open position.

Fig. 4 is a perspective detail view showing a modified method of mounting a hinge butt and showing a slight modification in the construction of the butt.

Fig. 5 is a view similar to Fig. 3 but showing another modification; and,

Fig. 6 is a view similar to Figs. 3 and 4 but showing the method of attaching a sheet metal hinge butt.

In Figs. 1 and 2 of the drawings, I have shown at 10, part of a stationary support or

door frame which may constitute a part of a cabinet or body of any desired construction. At 11, I have shown a part of a door to be mounted in connection with the frame 10, and said door and door frame are preferably composed of sheet metal or partially of sheet metal. The part 10 where the door is to be hinged thereto is bent into channel formation to form an inner plate 10^a and side plate 10^b, extending in parallel relation to the side 10^c of the support and spaced therefrom, and the inner end of the plate 10^b is bent upon itself, and at right angles to said plate as shown at 10^d, to form a door stop limiting the inward movement of the door preferably at its free edge. The door 11 is provided at its edge portions with a box-shaped inwardly directed extension formed by oppositely arranged side walls 11^a and 11^b, an inner wall 11^c in spaced and parallel relation to the front wall 11^d of the door, the wall 11^b having a flange 11^e secured to the inner face of the front wall 11^d by welding or in any other desired manner. The wall construction above described forms a tubular chamber or compartment 12, which extends along the edge portions of the door and in alinement with the plate or flange 10^b when the door is in closed position.

The door 11 is hinged to the frame 10 by two or more of my improved hinges composed of two substantially similar butts 13, which in the construction shown in said figures, are formed from cast or die cast metal but which may be formed in any desired manner, each of said butts being U-shaped in cross sectional form, being provided with a side wall 14, and top and bottom walls 15 and 16, the outer faces of which are arc-shaped in cross sectional form. The inner adjacent faces of the top and bottom walls 15 and 16 are provided adjacent the outer ends of the butts when mounted in connection with their supports with pivot pin apertures for receiving pivot pins 17, note Fig. 3 and with grooves 18 opening through the rear ends of the hinge butts and adapted to receive pins 19 carried at the free ends of links 20 mounted upon the pivot pins 17 of the respective butts, said links being pivoted together centrally as seen at 21, as in the conventional type of concealed hinge link construction.

In mounting the hinge butts in connection with the frame 10 and door 11 in the manner shown in Figs. 1 and 2, the plate 10^b is aper-

tured as seen at 22 to conform with the contour of the upper and lower rounded portions of the butt forming an elongated elliptical aperture in which the outer end of the 5 butt is mounted so that the outer face of the butt lies flushly with the corresponding outer face of the plate 10^b. A similar aperture 23 is formed in the wall 11^a of the door as also seen in said figure. It is preferred that the 10 depth of the hinge butts 13 is such as to lie flush with the side wall 10^c of the cabinet and the wall 11^b respectively. In securing the butts in position, screws 24 are passed inwardly through the side wall 10^c of the support and into threaded holes 25 of the hinge butt mounted in connection therewith. In the construction shown, the screws enter the 15 upper and lower portions of the butts. In a like manner, screws 26 are passed through 20 the walls 11^b and into threaded apertures 27 of the butt mounted in connection with the door as clearly seen in Fig. 3 of the drawing. It will also be understood that if the 25 distance between the outer face of the butts and the rear ends thereof is not sufficient to fill the space between the walls 10^b—10^c, 11^a—11^b, shims or other spacing members may be coupled between the inner ends of the butt and the adjacent walls, it being understood however, that the butts may be 30 made to suit the requirements, especially where the volume will justify the construction of a special hinge butt to suit the particular use, and this applies to all forms of 35 construction herein described when mounted as shown in Figs. 1 to 3 inclusive.

In Fig. 4 of the drawing, I have shown a slight modification, wherein a hinge butt 28, of substantially similar form to the butts 13, 40 the only difference being that the upper and lower faces are square as seen at 29 instead of being rounded, is mounted in connection with its support 30 by screws 31 passed through one wall 30^a of the support and into one side face of the butt 28 or threaded apertures 32 formed in the upper and lower wall 45 portions of the butt. In this form of construction, the aperture 30^b in the wall 30^c of the support will be elongated and rectangular in form instead of substantially elliptical in form as in Figs. 1 to 3 inclusive. In 50 this method of mounting the butt, it is not essential that the rear end of the butt engage a wall of the support, nor is it essential that the wall 30^d of the support should contact with the butt. It is also preferred that the 55 inner end of the butt at the top and bottom thereof be provided with threaded apertures 33 to permit of the mounting of the butt in 60 the manner shown in Figs. 1 to 3 inclusive, if it is desired to do so. In other words, the butt may be manufactured with both of the apertures 32 and 33 therein to permit of its universal mounting, and the apertures 33 65 may extend transversely through the butt to

open at both sides thereof to permit of the mounting of the butt in connection with either side wall of a support.

In Fig. 5 of the drawing, I have shown another modification wherein the butt 34 having rounded top and bottom ends is 70 grooved transversely of the top and bottom thereof as seen at 35 to partially receive the shank of screws 36 passed through one wall 37 of a support, and in threaded engagement 75 with an opposite wall 37^a. With this construction, the butt is rigidly keyed in connection with the support to retain the same against displacement. It is also preferred 80 that the rear end of the butt 34 be provided with threaded apertures 38 to permit of the mounting of the butt in the manner shown in Figs. 1 to 3 inclusive.

In Fig. 6 of the drawing, I have shown another modification in which a hinge butt 39 composed of sheet metal is mounted in connection with a support 40, said body being substantially U-shaped in form and comprising a back wall 41, and top and bottom walls 42 and 43, the front ends of which 85 terminate in laterally extending flanges 44. In this construction, screws 45 are passed through one wall 40^a of the support and threaded into apertures formed in the back wall 41 of the butt in securing the butt in 90 position. It will also be noted that the aperture 40^b formed in the wall 40^c of the support, is rectangular to receive the U-shaped body of the butt, and the flanges rest in recesses 40^d in the wall 40^c of the support and formed by compressing the metal of said wall 95 backwardly, as seen at 40^e.

In all forms of construction shown, it will be seen that the front or exposed surfaces of the butts lie flush with the corresponding outer faces of their respective supports, and screws or other fastening devices are not seen, thus forming a neat and finished appearance, the attaching flanges commonly employed in hinge butts of the class under consideration being eliminated, thus effecting a saving in the cost of production and reducing the dimensions of the butts as well as the space required therefor in the 105 respective supports.

It will be understood that while I have shown certain details of construction for carrying my invention into effect and have illustrated a hinge of one type of construction, that my invention is not necessarily limited to the details of construction herein shown and described, and various changes therein and modifications thereof may be made within the scope of the appended 110 claims without departing from the spirit of my invention or sacrificing its advantages.

Having fully described my invention, what I claim as new and desire to secure by Letters Patent, is:—

1. In a sheet metal body having spaced 130

and parallel walls, a hinge butt adapted to be mounted in said body between said spaced walls, one of said walls having an aperture substantially similar to the peripheral contour of the butt and in which the butt is mounted so that the outer face of the butt will lie flush with the outer face of said apertured wall, and means mounted in connection with the sheet metal body and engaging said butt for retaining the same in connection therewith.

2. In a sheet metal body having spaced and parallel walls, a hinge butt adapted to be mounted in said body between said spaced walls, one of said walls having an aperture substantially similar to the peripheral contour of the butt and in which the butt is mounted so that the outer face of the butt will lie flush with the outer face of said apertured wall, and means mounted in connection with the sheet metal body and engaging said butt for retaining the same in connection therewith, said means involving screws passed through said body and engaging said butt inwardly of the outer face thereof.

3. A hinge for coupling two sheet metal butts together, said hinge comprising two substantially similar butt members, one of which is secured to one body and the other to the other, each of said bodies being apertured to receive the respective butts which fit snugly in said apertures, and the outer faces of which lie flush with the corresponding faces of said bodies, hinge links for coupling the butts together, and means mounted in connection with said sheet metal bodies and engaging said butts inwardly of the outer face thereof.

outer faces thereof for securing the butts to their respective supports.

4. A hinge for coupling two sheet metal butts together, said hinge comprising two substantially similar butt members, one of which is secured to one body and the other to the other, each of said bodies being apertured to receive the respective butts which fit snugly in said apertures, and the outer faces of which lie flush with the corresponding faces of said bodies, hinge links for coupling the butts together, and means mounted in connection with said sheet metal bodies and engaging said butts inwardly of the outer faces thereof for securing the butts to their respective supports, said means comprising screws passed through said bodies and in threaded engagement with said butts.

5. In a hinge comprising two butts, one of which is secured to a stationary support and the other to a swinging support and links pivotally coupling the separate butts together, one of said butts comprising a substantially U-shaped body adapted to be mounted in and contained within the boundaries of one of said supports, the channel of said body opening outwardly through the support with the outer and exposed face of the butt flush with the corresponding face of the support, and means on the support engaging the U-shaped body of the butt inwardly of the outer and exposed face thereof for retaining said butt within and to the support.

In testimony that I claim the foregoing as my invention I have signed my name this 28th day of February, 1927.

JOSEPH SOSS.
